BROACHING MACHINE

Harry H. Gotberg, Detroit, Mich., assignor to
 Colonial Broach Company, Detroit, Mich., a
 corporation of Delaware

Application June 17, 1943, Serial No. 491,149

16 Claims. (Cl. 90—33)

The present invention relates to a surface broaching machine of the type adapted to make a plurality of successive cuts on a single workpiece with the same broaching tool, and this application is a continuation-in-part of applicant's copending application, Serial No. 478,497, filed March 9, 1943.

It is the general object of the present invention to provide improved means for operating and controlling the movement of the work holding fixture, or table, during the successive broaching operations. More specifically, it is an object of the present invention to provide an improved means for limiting movement of the table toward the broach at a plurality of successively advanced positions for the corresponding number of broaching strokes.

Another object of the invention is to provide means of the above-mentioned character which will positively lock the work table in position during the broaching stroke and which will prevent cocking of the table under broach cutting pressure.

Another object of the invention is to provide improved means of the type mentioned which, upon completion of one cycle of movement, is automatically placed in a position to begin a new cycle.

Other objects and advantages of the invention will become apparent from the following specification, the drawings relating thereto, and from the claims hereinafter set forth.

In the drawings, in which like numerals are used to designate like parts in the several views throughout:

Figure 1 is a front elevation of a vertical broaching machine to which the invention may be applied;

Figure 2 is a side view of the broaching machine shown in Figure 1;

Figure 3 is a fragmentary sectional view taken on the line 3—3 of Figure 1, showing a plan view of the work moving fixture;

Figure 4 is a sectional view, the upper portion of which is taken on the line 4—4 of Figure 3 and the lower portion of which is taken on the center line of the machine, as indicated by the line 4—4 in Figure 7;

Figure 5 is a side elevation of the work supporting fixture and adjustable abutment mounted on the table;

Figure 6 is a view similar to Figure 5, showing the parts in a different position;

Figure 7 is a view taken on the line 7—7 of Figure 4;

Figure 8 is a fragmentary section taken on the line 8—8 of Figure 3;

Figures 9, 10 and 11 show the form of workpiece for which the particular embodiment of the invention illustrated is constructed;

Figure 12 shows a modified form of abutment cam for use when a relatively few number of successive broaching steps is required on each workpiece;

Figure 13 is a hydraulic circuit diagram showing the hydraulic circuit controls and cylinders provided to effect automatic operation of the machine through a complete cycle of broaching strokes; and

Figure 14 is a fragmentary view of a portion of the hydraulic circuit, showing the manner in which the indexing mechanism must be modified to accommodate the modified form of abutment cam shown in Figure 12.

Referring to the drawings, the invention is shown applied to a vertical broaching machine having a main frame 10 and a vertically movable broaching slide 11, which is formed integrally with a hydraulic cylinder 12 which is reciprocated with reference to a stationary piston under the control of the hydraulic circuit hereinafter described. Mounted on the slide 11 is a face plate 12' carrying a pair of tool holding channel-shaped members 13. In the present instance, the machine is designed for operating upon two workpieces simultaneously and for simultaneously cutting two relatively deep notches in each of the workpieces. Consequently, the tool holding channels support four broaching tools 14.

The frame of the machine includes a forwardly projecting portion having a top surface 15 defining a horizontal slide on which is mounted the work moving and supporting table 16. A pair of retaining plates 17 located at opposite sides of the work table is fixed to the top surface 15 of the frame and overlies the edges of the work table 16 to retain the table in position while permitting it to reciprocate toward and from the broach.

The top frame member 15 contains a longitudinally extending slot 18 at its center, into which projects a downwardly extending rib 19 on the table 16. Journaled in a sleeve 20 on the table is a centrally located vertical pin 21, the lower end of which is formed into a rectangular shoe 22 which lies below the bottom surface of the rib 19 and also below the bottom surface of the member 15 of the frame. The shoe 22, which is of hardened steel, fits in a hardened steel cam groove 23 formed in a transverse slide 24, which is mounted in suitable ways on the under-

side of the frame member 15 for movement transverse to the movement of the table 16. The slot 23 is diagonal, as best shown by dotted lines in Figure 3, in consequence of which transverse reciprocation of the slide 24 effects longitudinal reciprocation of the table 16. Such transverse reciprocation of the slide 24 is effected by a movable cylinder 26, which is keyed to the slide 24 by key 27 and which slides upon a pair of aligned stationary piston rods 28 and 29 fixed to the frame of the machine.

The arrangement of the means for reciprocating the table so far described is substantially like that disclosed in the patent to Benedict Welte et al., No. 2,225,191, except that the cam groove in the present instance is straight, rather than arcuate, and the angle of the cam groove 23 in the present construction is a self locking angle, that is to say it is such an angle that no force exerted on the table will be effective to cause movement of the slide 24 regardless of the position of the shoe 22 in the groove 23.

A work holding fixture is mounted upon the table 16 and includes means for locating the position of the table during the broaching operations. This fixture comprises a main casting, indicated generally at 30. The casting 30 includes a flat base portion 31 secured to the table 16 in any suitable manner, as by bolts 32 and a pair of transversely aligned bosses 33 and 34, the outer ends of which are enlarged to form housings 35 and 36, respectively. The casting 30 also includes a pair of longitudinally extending housings 37 and 38 in longitudinal alignment with the housings 35 and 36, respectively, and projecting rearwardly therefrom. It will be noted from Figures 3 and 7 that the housings 37 and 38 extend outwardly at the sides beyond the side edges of the base portion 31 of the casting 30, thereby defining a pair of side recesses beneath the housings 37 and 38. The casting also includes an upstanding work locating block 39, which is of generally T shape, as viewed in plan in Figure 3, and a pair of reinforcing ribs 40 and 41 extending between the work supporting member 39 and the bosses 33 and 34, respectively. The work supporting member, or block, 39 is provided with two right angle notches in its forward corners, as best shown in Figure 3, to receive a pair of workpieces 44. Suitable hardened steel wear plates 45 are secured to the sides of the right angle notches to form the workpiece locating surfaces.

The workpiece, as best shown in Figures 9, 10 and 11, is of generally rectangular configuration except that it has an arcuate or semi-circular groove 45 in its upper surface. The particular operation to be performed on the workpiece by the machine illustrated is a notching operation in the forward corners to form notches 46, the metal to be removed being indicated by the dotted lines in Figures 11.

Each workpiece is held in position after it is seated against the wear plates 45 by means of a clamp 48, of generally right angle configuration with its downwardly extending leg 49 arcuately curved to fit the semi-circular groove, or channel, 45. The clamp is held in position by means of a stud 50 secured in the bottom of a recess 51 in the top of member 39 and extending through a suitable opening in the clamp 48. The clamp is tightened by means of a nut 52 and a spring 53 surrounds the stud and tends to urge the clamp upwardly to facilitate release thereof.

It will be understood that the present invention is not limited in its application to the particular operation illustrated or to any particular form of workpiece, and that suitable means may be provided to hold any form of workpiece on the broaching machine.

Fixed to the upright portion of the frame of the machine at each side of the broaching slide are fixed abutments 56 which may be held in position in any suitable manner, as by bolts 57. One of the fixed abutments 56 has a longitudinal opening 58 extending therethrough in which is slidably mounted a push rod 59, for a purpose hereinafter described.

When the table 16 advances with the work supporting fixture, one end of each of a pair of rods 60 carried by the fixture is adapted to abut against the fixed abutments 56 respectively and limit further movement of the table and workpiece toward the broach.

The rods 60 are rectangular in cross section and are slidable in rectangular slots 61 in the housings 37 and 38 of the fixture casting 30. The slots 61 in the housings 37 and 38 are closed by means of a pair of plates 63 and 64, the forward ends of which are enlarged to complete the walls of the housings 35 and 36, respectively. The bottoms of the slots 61 are provided with suitable slots 66, as best shown in Figure 4, to receive pins 67 which are fixed respectively in the rods 60. Coil springs 68 connect the pins 67 to stationary pins 69, thus normally urging the pins 67 and, consequently, the rods 60 to the left, as viewed in Figure 4, the slots 66 permitting such movement.

A pair of stationary stops 70 secured to the stationary retaining plates 17 limits maximum movement of the pins 67 and rods 60 to the left, as viewed in Figure 4, to the position shown in that figure. In this position, the rods 60 are out of contact with the abutments 56, thus permitting the push rod 59 to project from its abutment 56.

Means are provided on the fixture for automatically controlling the position of the rods 60 in order to limit movement of the work table toward the broach. The means includes a relatively heavy shaft 72 journaled in the two bosses 33 and 34 extending transversely to the table 16. The ends of the shaft 72 project into the housings 35 and 36, where they are reduced in diameter, as indicated at 73, and receive a pair of rotatable abutment elements 74. The two abutment elements, which are identical in construction, are keyed to the shaft 72 by means of a key 75 and are peripherally formed of a plurality of stepped, flat surfaces 76, 77, 78, 79, 80, 81, 82, 83, 84, 85, 86 and 87, circumferentially distributed in sequence around the periphery and of progressively decreasing distance from the axis of the shaft 72. The surfaces are so arranged that upon rotation of the shaft 72 any one of the flat surfaces 76 to 87, inclusive, may be brought into position to abut against the ends of rods 60. In this connection, it will be noted that the rods 60 extend in a line intersecting the axis of the shaft 72 and, consequently, no pressure exerted between the rods 60 and any one of the surfaces 76 to 87, inclusive, will have a tendency to rotate the abutment elements 74.

The right-hand end of shaft 72, as viewed in Figure 7, beyond the rotatable abutment element 74 thereon, is still further reduced in diameter, as indicated at 90, to receive a ratchet wheel 92, shown best in Figure 4. The ratchet

wheel is locked in position on the shaft 72 by any suitable means, such as washer 93 and a nut 94, which is threaded on the extremity of the shaft 72. The opposite end of the shaft 72 is not provided with a corresponding ratchet wheel, but the abutment element 74 on the opposite end is held against displacement by a pair of washers 95 and 96 and a nut 97 on the end of shaft 72.

Means are provided for engaging the ratchet 92 and automatically indexing the shaft 72 on each reciprocation of the work table 16. This means includes an L-shaped block 100 fixed in any suitable manner, as by cap screws 101, to the right-hand stationary retaining plate 17 on one side of the right-hand edge of housing 36. Slidably mounted on block 100 is a pawl carrier 103 which may be adjusted in position longitudinally of the plate 17 by means of an adjusting screw 104 threaded in the upstanding leg of the L-shaped block 100. The pawl carrying block 103 may be held in adjusted position by means of a stud 105, which extends through a slot 106 in the pawl carrier 103 and is secured in the block 100.

The pawl 108 is pivoted on member 103 by means of a stud 109 held in position by a pair of nuts. The pawl 108 lies in a recess 110 formed on the inner side of the pawl carrier 103. A suitable spring 111, shown best in Figure 4, is provided for normally urging the pawl in an upward direction to engage the ratchet wheel 92. It will be apparent that as a result of this construction when the table 16 withdraws from the broach the pawl 108 will engage a tooth of the ratchet wheel and index the ratchet wheel one notch in a counterclockwise direction, as viewed in Figures 4, 5 and 6.

The coverplate 64 for the housing 36 is cut away at 112 to make room for the block 100 and pawl carrier 103 when the table withdraws from broaching position to the position shown in Figure 4. As best shown in Figure 8, a spring pressed detent 116 is provided in boss 34 and is adapted to engage in any one of a plurality of notches 117 in the shaft 72 for retaining the shaft against accidental displacement from any one of its plurality of indexed positions. One notch is provided for each of the flat surfaces 76 to 87, inclusive, on the rotatable abutment members 74.

The mechanism operates in the following manner. The starting position of the machine is illustrated in Figure 4, in which position the work table 16 is fully withdrawn from broaching position and the ratchet pawl 108 has just completed indexing of the rotatable abutments 74 to return them to the position they assume at the start of the broaching cycle. In that position, flat surfaces 76 on the abutments 74 are in position to engage the plunger 60 but are actually out of contact with the plunger by reason of the fact that movement of the plunger 60 to the left, as viewed in Figure 4, is limited by engagement between pins 67 and the stationary stops 70. In this position of the parts, a dog 118 on a rearward projection of the table 16 has engaged a lever 119, which is pivotally mounted upon a stationary bracket 120, and shifted the lever 119 in a counterclockwise position, thereby causing the lever to force the rod 121 to the right, as viewed in Figure 4. The rod 121 actuates a control valve, hereinafter described, which effects return of the broaching

cylinder and broach to their upper or starting positions, shown in Figure 4.

As soon as the broach reaches its upper position, the machine automatically stops to permit insertion of a pair of new workpieces in the fixture. When this is done, the machine is started and the first movement is a movement of the worktable toward the broach. During such movement, the flat surfaces 76 on the rotatable abutments 74 engage the ends of the rods 60 and force the rods rearwardly against the stationary abutments 56, thereby limiting movement of the table toward the broach. In view of the fact that the table is driven by means of a hydraulic cylinder through self-locking cam groove 23, the cylinder will wedge the table in broaching position with the plunger 60 forced tightly against the stationary stops 56. Since the driving connection between the cylinder 26 and the table 16 is located centrally of the table and between the stationary abutments 56, the wedging action will positively prevent cocking of the table under any of the loads to which it is subject during the broach cutting operation.

Completion of this forward movement of the table will cause the push rod 59 in the stationary abutment 56 to be moved to the right, as viewed in Figure 4, to the position shown in Figure 5, and the push rod is connected to a suitable control valve, hereinafter described, which initiates the downward or broach cutting stroke of the broaching cylinder and broaches 14. The rod 59 is also mechanically connected to rod 121 in such a manner that upon movement of the rod 59 into its abutment 56 the lever 119 will be swung in a clockwise direction from the position shown in Figure 4, as hereinafter described in greater detail. On this first downward movement of the broaches, the broach cutting operation is performed on the workpieces. When the broaches reach the bottom of their downward and broaching stroke, suitable valve means are operated to move the cylinder 26 to the left, as viewed in Figure 7, in order to retract the table to the position shown in Figure 4. Upon such retraction, the pawl 108 indexes the rotatable abutments 74 to a position in which the flat surfaces 76 are in alignment with the rods 60.

The table return movement also returns lever 119 to the position shown in Figure 4, thereby causing return of the broaches to their upper position. The table then makes its second advancing movement, this time moving a slightly greater distance than before due to the fact that the flat surfaces 76 on the rotatable abutments 74 are spaced at a less distance from the axis of the shaft 72 than are the flat surfaces 76. Consequently, on repetition of the broaching stroke of the broaches 14 a further cut will be made in the workpieces. The cycle may repeat itself in this manner any desired number of times up to a maximum of twelve when the particular abutment means shown is employed.

On each retraction of the table 16, the rotatable abutments 74 are indexed, and on the subsequent advancing movement of the table it moves to a slightly greater extent toward the broach than on the previous stroke due to the fact that the successive abutment surfaces 76 to 87, inclusive, are a progressively less distance from the axis of the shaft 72.

With reference to the above statement that the cycle may be repeated, it should be noted that

twelve (12) abutment surfaces are provided on the rotatable abutments 74. Accordingly, if two workpieces are simultaneously machined, twelve (12) or less complete broaching cuts may be made on each workpiece. It is, however, possible to operate the machine on a single workpiece at a time, taking a plurality of successive cuts on one broaching tool and then shifting the workpiece to the second fixture and completing the cycle on the second or finish broaching tool. The particular hydraulic circuit mechanism hereinafter described is designed to provide a two-stage broaching operation on a single workpiece at a time in that manner. Accordingly, the machine automatically provides a cycle of eleven (11) broaching strokes and then stops to permit the operator to shift the workpiece from one fixture to the other. Then, on restarting the machine it makes a single broaching cut on the work fixture with the finishing broach and again stops, whereupon the operator removes the finished workpiece and places a new workpiece in the first fixture, the parts then being in position to repeat the complete cycle.

It will be apparent that other variations in the sequence of operation of the machine may be made.

Regardless of the manner in which the machine is utilized, it will be apparent that during the last broaching stroke the parts will be in the position illustrated in Figure 6, in which the flat surfaces 87 on the rotatable abutments 74 engage the rod 60. On withdrawal of the table from the position shown in Figure 6, which withdrawal completes the entire cycle of operation, the rotatable abutments 74 will be indexed in the position shown in Figure 4, in which figure all parts are shown in position to start a complete cycle.

It will be apparent that the number of steps on the rotatable abutments 74 may be varied to suit the needs of the machine and that different shaped abutment cams may be substituted from time to time, as required. It will also be apparent, however, that if it is desired to perform a complete multiple broaching cycle in which there are fewer than six or eight broaching strokes, it will be difficult, if not impossible, to index the rotatable abutments 74 through a complete revolution for each complete cycle by means of the pawl and ratchet construction illustrated. Accordingly, when a relatively few number of strokes per cycle is required, it is preferred to construct the rotatable abutments in the manner illustrated in Figure 12, wherein is shown a view corresponding to Figure 4 but of a modified construction of an abutment cam adapted for use when the complete cycle contains only two broaching strokes of the ram.

In the modified construction, the rotatable abutment 74' is provided with eight abutment surfaces, indicated 76', 77', 78', 79', 80', 81', 82' and 83', and the ratchet wheel 92' is provided with eight correspondingly positioned teeth so that one or more of the faces 76' to 83' will be in position to abut the rod 60' after one tooth of the ratchet wheel has been engaged and shifted by the pawl 108' at the end of the withdrawal stroke of the table 16'. The four abutment faces 76', 78', 80' and 82' of the rotatable abutment 74' are positioned at equal distances from the axis of the abutment and are separated from each other by the intermediate abutment faces 77', 79', 81' and 83', the latter group also being equally spaced from the axis of the abutment 74' but being located closer to the axis of the abutment faces

than the first group. All other portions of the machine, except for a minor change in the hydraulic circuit hereinafter referred to, are identical to the machine described in connection with Figures 1 to 11.

It will be apparent that when the modified form of rotatable abutment shown in Figure 12 is employed, the work fixture will move from its initial position, illustrated in Figure 12, toward the broach until the abutment 74' engages the rod 60' and the latter has engaged the fixed abutment 58, not shown in Figure 12. Thereby the first broaching stroke of the ram will take place. Upon completion of the first broaching stroke, the table will retract, and during such retraction the pawl 108' will engage the next tooth of the ratchet wheel at 92' and shift the rotatable abutment in a counterclockwise direction until the abutment surface 77' is in position to engage the end of the rod 60'. Thus, on the next work advancing movement of the table 16' the table will move to a greater distance toward the broach than it would on its first stroke and, consequently, the broach will make the second cut in the workpiece. On the second retraction of the work table, means, hereinafter described in connection with the hydraulic circuit, will bring the machine to a stop, thus ending a complete cycle of operations. However, the machine is in a position to be started on the second cycle, in which event the first broaching stroke will occur when the abutment surface 78' engages the end of rod 60' and the second broaching stroke will occur when the surface 79' engages the rod 60' to locate the table. It is apparent, therefore, that in the modified construction four complete cycles are provided for each revolution of the rotatable abutment, instead of the single rotation as in the embodiment previously described. The mode of operation is, however, the same.

It will be understood that any desired number of abutment surfaces may be provided upon the rotatable abutment so long as there are at least six and preferably eight surfaces, since effective operation of the pawl and ratchet mechanism requires at least six and preferably eight teeth on the ratchet wheel. Accordingly, the rotatable abutment will be provided with abutment surfaces which in number constitute an even multiple of the number of broaching strokes in a complete cycle but not less than six or eight. For example, if the complete cycle contains three broaching strokes, the rotatable abutment may have six abutment surfaces but is preferably constructed with nine, since the larger number results in a more satisfactory pawl and ratchet operation.

While any suitable hydraulic control mechanism may be provided for controlling the operation of the machine through its cycle of movement, there is illustrated diagrammatically in Figure 13 one form of hydraulic circuit which is adapted to operate the machine automatically through eleven (11) successive cutting strokes and then stop the machine to enable the workmen to shift a workpiece from the roughing fixture to the finishing fixture. When the machine is then manually started on its finish broaching stroke, it completes that stroke and retracts the table and again automatically stops to enable removal of the finished workpiece and insertion of a new workpiece. The parts are then in the position to begin a complete new cycle of operation.

Referring to Figure 13, the main broaching slide cylinder is indicated at 12 and the cylinder for operating the table is indicated at 26. Fluid is supplied through suitable lines and valves to these two cylinders from a pair of pumps 125 and 126, which are located within a tank or fluid reservoir 127. Pumps 125 and 126 supply the broaching cylinder 12 through a line 128, a pilot control and overload by-pass valve 129, a line 130, a speed control valve 130', a line 131, and a pilot controlled four-way valve 132 which has a pair of lines 133 and 134 leading to opposite ends of the cylinder 12. Line 134 is connected directly to the lower end of cylinder 12 through the piston rod 135, while line 133 connects to a foot valve 136 which, in turn, is connected to the upper end of the cylinder 12 by a line 137 and an auxiliary piston rod indicated diagrammatically at 138. In the actual construction, the two piston rods 135 and 138 are concentric, and the fluid to the upper end of the cylinder flows between the two rods.

Fluid from the pump 126 flows through line 140 to a pilot controlled overload relief valve 141 and thence through line 142 to a pilot controlled four-way valve 143, which has a pair of lines 144 and 145 leading to the piston rods 28 and 29, respectively, of the cylinder 26. The fluid which flows through piston rod 28 passes into the right-hand end of the cylinder 26 through an opening 146, while the fluid flowing through the piston rod 29 flows into the opposite end of cylinder 26 through an opening 147.

The pilot controlled overload relief valve 129 provides a clear, unobstructed flow between lines 128 and 130, and the stem 150 of the valve normally closes the lower port, which is connected through line 151 and line 152 to the tank 127. The stem 150 is provided with a piston 153, which fits the valve housing and which is provided with a small bleed opening 154. Accordingly, the pressure in lines 128 and 130 which exists in the main chamber of the valve housing 129 is transmitted through the bleed opening 154 in the piston 153 to the upper chamber of the valve housing, thereby balancing the valve stem hydraulically. A light spring 155 holds the balanced valve in its lower position, in which it closes the port connected to line 151.

The space above the piston 153 is connected through a passage 156 and a connecting passage 157 to a ball check valve 158, which is normally held in position to block passage 157 by the action of a spring 159. If the pressure in lines 128 and 130 exceeds a predetermined amount determined by the setting of spring 159, the ball check valve 158 will open, thereby venting the fluid above piston 153 through a passage 160 and through an axial bore 161 in the valve stem to the tank lines 151 and 152. The flow of fluid through the bleed opening 154 is restricted, and it cannot replace the fluid above the piston 153 as fast as it discharges to the reservoir past the check valve 158. Consequently, the pressure above the piston 153 will be less than that below the piston, and the valve stem will move upwardly, opening the port connected to line 151. This permits the fluid from pump 125 to discharge back to the tank at very low pressure.

The stem 150 of valve 129 may also be caused to raise at any time during the operation of the machine by connecting pilot line 162 to the tank 127 in the manner hereinafter described. When

this occurs, the pressure above the piston 153 drops and the valve opens.

The valve 130' may be any suitable form of speed control valve. It is set to pass a desired portion of the fluid supplied to line 130 through line 163 to the tank line 152, in order to decrease the speed of the broaching stroke.

Except for its control upon the rate of flow of fluid to the main cylinder 12, the speed control valve 130' performs no function and can be omitted if desired, in which event line 130 would be connected directly to line 131.

The four-way valve 132 is of the spring centered type, the spool 166 being normally held in the position shown in the drawings by means of a spring centering device including a pair of washers 167 and 168 loosely fitting the stem of the valve spool and a spring 169 which surrounds the stem and bears against the two washers. Washer 167 is adapted to bear against the right-hand land of the valve spool 166, while washer 168 bears against sleeve 171, which is fixed to the valve stem. The washers also seat at their outer peripheries against shoulders formed on the valve casing.

When no pilot pressure is applied to either end of the valve the spring centering device shifts the valve spool to the position shown, in which position fluid may flow from line 131 into the annular groove 173 and thence through notches 174 in the central land of the valve spool and thence through notches 175 in the right-hand land of the valve spool to channel 176, which communicates through a passage 177 with the tank line 152. Accordingly, no pressure is applied to line 134. The left-hand land of the valve spool blocks return flow from line 133 to the tank line 152, which is also connected by means of passageway 177 in the valve housing to annular channel 178.

When pilot pressure is applied to the right-hand end of valve 132 through pilot line 180, the valve spool is shifted to its left-hand end, during which movement sleeve 171 compresses spring 169. In its left-hand position, valve 132 permits flow of fluid under pressure from line 131 to line 134, inasmuch as the notches 175 in the right-hand land are shifted out of registry with the channel 176 when the spool is in its left-hand position. In this position the left-hand land of the valve spool clears channel 178, with the result that fluid from line 133 may return to the tank through channel 178, passageway 177 and tank line 152.

When pilot pressure is admitted to the left-hand end of valve 132 through pilot line 183, the central land of the valve spool shifts to the right of channel 173, permitting flow of fluid under pressure from line 131 to line 133. Channel 178 remains closed by the left-hand land of the valve spool, and the right-hand land of the valve spool clears channel 176, thus permitting return flow from line 134 through channel 176 and passageway 177 to the tank line 152.

The foot valve 136 contains a spring pressed check valve 184 which is normally held closed by a light spring 185, in consequence of which a relatively free flow of fluid is permitted through valve chamber 186, passageway 187, past check valve 184, through passageway 188 and valve chamber 189 to line 137.

Communication between valve chambers 189 and 186 is normally closed by means of the valve spool 190, which is held in its lower position by means of a spring 191 positioned within the hol-

low valve spool. The valve contains a third chamber 192, which is fitted by a piston 193 on the valve spool 190, and a small bleed opening 194 connects chambers 189 and 192 at a point beneath the piston 193 in the latter chamber. As a result of this construction, when line 133 is connected to the tank line 152 by valve 132 the pressure in line 137 from the upper end of cylinder 12 will be communicated from chamber 189 through the bleed opening 194 to the lower portion of the chamber 192 beneath piston 193 and tend to raise the valve spool. However, the spring 191 is so set that it will hold the valve spool closed against that pressure in line 137 caused by the weight of the broaching slide but will permit the spool to raise and open the valve at a slightly higher pressure. This prevents the slide from falling by its own weight during the broaching stroke if, for any reason, the resistance to its downward movement decreases sufficiently to permit it to so fall.

When the machine is not in the broaching or return strokes of its cycle, valve 132 assumes its mid position shown in the drawings and thereby blocks return of fluid from line 133. This also prevents the cylinder 12 from falling by gravity under these conditions.

The pilot controlled overload relief valve 141, which connects lines 140 and 142, is identical in construction and mode of operation to the valve 129, previously described, and hence will not be described in detail.

It is sufficient to note that the valve 141 always permits free flow from line 140 to line 142; but if the pressure in lines 140 and 142 exceeds a predetermined amount, the valve spool will open, permitting discharge of the fluid under pressure through line 196 to the tank line 152. The spool of valve 141 may also be opened at any time during the cycle of operation by connecting pilot line 197 to the tank in the manner described in connection with valve 129.

Four-way valve 143 is generally similar to four-way valve 132 except that the spool of valve 143 is not spring centered but, on the contrary, is held in either one of its two extreme end positions by means of a spring pressed detent 200 which engages in either one of the pair of notches 201 and 202 in the valve spool.

When pilot pressure is admitted to the right-hand end of valve 143 through pilot line 205, the spool is shifted to its left-hand position, shown in the drawings, in which position fluid under pressure from line 142 flows between the central and right-hand lands on the valve spool to line 145 and thence to the left-hand piston rod 29 of the work table moving cylinder. At this time, fluid from the right-hand piston rod 28 of the work table moving cylinder returns through line 144 and the space between the left-hand and central lands of spool 203 to channel 206, which connects through a passageway 207 to a line 208. Line 208, in turn, connects through line 196 to the tank line 152.

When pilot pressure is admitted to the left-hand end of valve 143 through pilot line 209, valve spool 203 is shifted to its right-hand position, in which position fluid under pressure from line 142 flows between the central and left-hand lands of the spool 203 to line 144. Return flow through line 145 passes between the central and right-hand lands to channel 210, which connects with passageway 207 and tank line 208.

When there is no pilot pressure applied to either end of valve 143, the valve spool is held

against displacement from the position it last assumed by means of the spring pressed latch 200.

Operation of the above described main control valves to effect an automatic cycle of operation of the machine is accomplished through a pilot controlled valve system which includes three main control valves and a number of auxiliary valves. The three main control valves are the manually operated control valves 215, a table operated pilot valve 216 for controlling the operation of the main broaching cylinder 12, and a dual broaching slide controlled pilot valve 217-218 for controlling the operation of the work table.

The manual control valve 215 comprises a generally cylindrical body having a central bore provided with a plurality of axially spaced, circumferential grooves 220, 221, 222, 223, 224, 225 and 226. The grooves 220 and 226 are simply to accommodate drainage, and have no function except to dispose of fluid which leaks past the end lands on the valve spool. Slidable within the central bore is a valve spool 230, which is provided with four lands 231, 232, 233 and 234. The spool is normally held in the central or neutral position shown in the drawings by means of a spring 236, which bears at one end against the bottom of a cup-shaped sleeve 237 fixed to the right-hand end of the spool and at the other end against a washer 237' which loosely surrounds the valve stem.

The outer periphery of the sleeve 237 has an annular wide recess 238 and a second narrow annular recess 239. A spring pressed plunger 240 is normally urged into one or the other of the recesses 238 and 239. The spool is shifted by means of an operating rod 242, which is connected to an operating handle 243 pivoted in a convenient place on the frame of the machine. When no pressure is applied to the handle 243, the spring 236 shifts the sleeve 237 and, consequently, the spool 230 to the position shown in the drawings in which a spring pressed plunger 240 engages the right-hand edge of the wide annular recess 238. When the handle 243 is shifted to the left to start the machine, the valve spool is shifted by an amount equal to the width of the annular recess 238, with the result that when the operator releases the starting handle the spool is returned to its neutral position by spring 236. If the handle 243 is shifted in a right-hand direction from the neutral position, the spring pressed plunger 240 will engage in the annular recess 239 and retain the spool in its right-hand position until it is returned by operation of the handle 243.

The table controlled pilot valve 216 has a generally cylindrical body having a central bore in which is provided a plurality of annular channels 250, 251, 252, 253 and 254. Channels 250 and 254 are connected by passageway 256 to a pilot line 257, which is connected, in turn, to a pilot line 258 extending to the tank 127. Valve 216 is provided with a spool 260 having a pair of lands. The spool 260 is operated by means of a rod 261, which is shifted in its left-hand direction, as viewed in the drawings, by means of a lever 262 pivoted on a stationary portion of the machine and operatively connected to the push rod 59 in the fixed abutment 56, shown best in Figure 4. Consequently, when the work supporting table moves into broaching position, push rod 59 will be shifted to the right, causing

movement of the valve spool 260 into its left-hand position.

When the work supporting table is fully retracted from broaching position, as shown in Figure 12, dog 118 engages lever 119, which, in turn, shifts rod 121 to the right, rocking bell crank lever 264, which is pivoted on a stationary portion of the machine. Bell crank lever 264 operates a rod 265 which, in turn, operates a bell crank 266 in a clockwise direction. The upper arm of bell crank 266 is connected to the rod 261 by any suitable means, such as by projecting into a slot in the enlarged portion of rod 261, so that clockwise rotation of the bell crank will shift rod 261 and spool 260 to their right-hand position, shown in Figure 12. The valve spool 260 is provided at its right-hand end with a pair of grooves 268 and 269, which are adapted to receive a spring pressed plunger 270 which operates to retain the spool 260 in either one of its two adjusted positions.

The dual pilot valve 217 and 218 is, in reality, two separate valves mounted on a common operating shaft, indicated diagrammatically by the line 275. The operating shaft 275 carries a pair of fingers 276 and 277, which are adapted to be operated, respectively, by a pair of dogs 278 and 279 mounted upon the broaching slide 12. The fingers 276 and 277 are displaced from each other transversely of the axis of the cylinder 12, and the dogs 278 and 279 are likewise so displaced; so that the dog 278, which operates finger 276, will not engage finger 277, and dog 279, which operates finger 277, will not engage finger 276.

When the broaching slide 12 reaches its upper position, dog 278 engages finger 276 and rotates shaft 275 and, consequently, the rotary spools 280 and 281 of the valves 217 and 218 in a clockwise direction, to the position shown in Figure 12. With the spools 280 and 281 in the position shown in the drawings, fluid may flow through valve 217 from port 282 to port 283 through a passageway 284 in the valve spool while ports 285 and 286 are connected through passageway 293. At the same time, fluid will flow through valve 218 from port 288 to port 289 through passageway 290 in the valve spool and ports 291 and 292 are connected through passageway 294.

When the broaching slide 12 reaches its lowermost position, the dog 279 engages the finger 277 and rotates the shaft 275 and, consequently, valve spools 280 and 281 in a counterclockwise direction to a position in which the flow through valve 217 is from port 282 to port 285 and ports 283 and 286 are connected through passageway 293 in the spool. At the same time, the flow through valve 218 is from port 288 to port 291 and from port 289 through passageway 294 to port 292.

It will be observed that port 285 of valve 217 is connected to the pilot line 183 at the left-hand end of the four-way valve 132 by means of a pilot line 300 and a four-way reversing valve 301. The flow through the four-way reversing valve is normally from port 302 through passageway 303 in the rotatable valve spool 304 to port 305. It will also be observed that port 289 of valve 218 is connected to pilot line 180 at the right-hand end of the four-way valve 132 through a pilot line 309 and the four-way valve 301, the flow through the valve 301 being from port 310 to port 311 and thence to the pilot line 180. The four-way valve 301 is normally maintained in the position shown in Figure 12, but it will be observed that the pilot connections to the four-way valve 132 which control the direction of movement

of the broaching slide 12 may be reversed by shifting the four-way valve 301 to the right by means of handle 312, thus connecting port 302 to port 311 through passageway 303 and connecting port 310 to port 305 through passageway 313. This provides a relatively simple means for reversing the broaching ram in the event that the machine jams or otherwise stops during the broaching stroke.

10 Valve 316 is a combination check and pressure release valve, the purpose of which is to insure that the upper end of the broaching cylinder 12 is filled and, therefore, the broaching cylinder is in its top position before the work moving table begins to advance toward the broach. To accomplish this function valve 316, while it permits free flow from port 317 to port 318 through the spring pressed check valve 319, prevents return flow from port 318 to port 317 until the spool 320 is raised from the position shown in the drawings. Spool 320 is normally held in its lower position by a spring 321, and in that position it blocks flow between port 317 and port 318 except as permitted by the check valve 319. When the pressure in port 318 exceeds a predetermined value, the fluid from port 318 which acts through passageway 322 on the plunger 323, raises the valve spool 320 against the action of spring 321, and permits flow of fluid from port 318 to port 317, under the circumstances hereinafter described.

30 Valve 324 is a check valve connected by lines 325 and 325' between the port 318 of valve 316 and the main fluid line 137 to the upper end of the cylinder 12. This check valve, which is similar in construction to valves 350 and 352, hereinafter described, permits free flow from line 325 to line 325' but prevents reverse flow. Valves 316 and 324 co-operate in a manner hereinafter described to prefill the upper end of cylinder 12 before the work table can advance to broaching position.

40 Valve 326 contains a spool 327 having a land 328 which controls communication between ports 329, 330 and 331. The position of the land 328 determines whether or not the machine will stop at the end of a broaching cycle or will repeat the broaching cycle automatically. In the position shown in the drawings, the land 328 blocks communication between ports 329 and 330 and hence will cause the machine to stop at the end of its broaching cycle. If, however, the spool 327 is shifted to the right, thus providing communication between ports 329 and 330, the machine will automatically repeat the broaching cycle until such time as the spool 327 is shifted.

45 The position of the spool 327 is controlled by an indexing mechanism including a dog 334, which is pivoted to a fixed portion of the machine and bears on a roller 335 on the stem of the valve spool 327. The position of dog 334 is controlled by engagement of a point 336 on the dog with the periphery of a disc 337. The disc 337 in the particular machine illustrated is provided with a pair of notches 338 and 339. A spring 340 bearing on the right-hand end of the valve spool 327 normally urges the spool to the left and, when the disc 337 is in position for the point 336 of dog 334 to fall into one of the notches 338 or 339, the spool 327 will shift to the position shown in the disc and cause stoppage of the machine. Disc 337 is fixed to a ratchet wheel 342 which, in turn, is actuated by a pawl 343 carried by the rod 344 of a piston 345 in a cylinder 346. Piston 345 is reciprocated once for each cycle of operation of the machine by the admission of fluid to the ports 347 and 348.

in the manner hereinafter described. A spring 349 acts to hold the pawl 343 at all times in engagement with the ratchet 342.

As previously indicated, valves 141 and 129 may be opened at any time in the cycle by connecting their respective pilot lines 197 and 162 to the tank. Such valve opening is utilized to stop the machine in an emergency. Pilot line 162 is connected to channel 221 of valve 215 through a check valve 350 and a line 351, while pilot line 197 is similarly connected to the channel 221 in valve 215 by a check valve 352 which, in turn, is connected by line 353 to the line 351.

When the manual control lever 243 is shifted to the right to its emergency stop position, land 232 on the valve spool 230 shifts to the right of channel 222, thus permitting communication between channels 221 and 222. Channel 222 is connected by means of a line 355 and a line 356 to the tank pilot line 258. Consequently, when the valve spool 230 is shifted to the emergency stop position, fluid may flow freely through the check valves 350 and 352 from the respective pilot lines 162 and 197 to the channel 221 of valve 215 and thence through channel 222 and lines 355, 356 and 258 to the tank, thereby causing the valves 141 and 129 to open and relieve the pressure on the system. The check valves 350 and 352 open freely against relatively light spring pressure to permit such flow, but they will not permit flow in a reversed direction.

The operation of the hydraulic circuit is as follows. In Figure 12, all of the parts are shown in the position they assume at the end of a complete cycle of operation of the machine, at which time the machine is automatically stopped to remove a finished workpiece and place a new workpiece in one of the two work holding fixtures. Assuming that the pumps 125 and 126 are operating, there will be no pressure applied to the broaching cylinder 12 because the main control valve 132 for the broaching cylinder is in its central position, in which the pressure fluid supplied through line 131 flows to the tank through channel 173, notches 174, notches 175, channel 176, passageway 177, and tank line 152. The fluid trapped in the upper end of cylinder 12 by valve 132 will hold the broaching cylinder in its upper position against the force of gravity acting on the cylinder. The fluid under pressure from pump 126 will be transmitted through line 140, valve 141, line 142 and valve 143 to line 145 and thence to the left-hand end of the work cylinder 26 through piston rod 29. Since the work table will be at its extreme outer position and cannot move further, the pressure will build up to a point at which valve 141 will open, venting the pressure from line 140 to the tank through lines 196 and 152.

The setting of valve 141 is such that it limits the pressure in the left-hand end of cylinder 26 during these circumstances to a safe maximum pressure. If at any time the pressure drops below the maximum, valve 141 will automatically close. In the meantime, high pressure is maintained on line 142 and the left-hand end of cylinder 26.

The source of pilot pressure for the entire circuit is line 360, which is connected to line 142 which at all times is subject to the pressure developed by pump 126. Line 360 connects to channel 252 of valve 216. When the machine is stopped in the position shown in the drawings, the pressure from channel 252 is communicated from channel 253 and thence to a line 361 which,

in turn, is connected to port 282 of valve 217. Line 361 is also connected to the left-hand end of cylinder 346, thus holding the piston 345 of the indexing mechanism in its right-hand position. The pilot pressure from port 282 of valve 217 is transmitted through passageway 284 to port 283 and thence through line 362 to the line 325, which extends between check valve 324 and port 318 of valve 316.

10 Since no flow can occur between ports 318 and 317 of valve 316 until the pressure has reached an amount determined by the setting of valve spring 321, the pilot pressure from line 363 will pass upwardly from line 325 through the check valve 324 to line 137 and thence to the upper end of the broaching cylinder 12 and help maintain the broaching cylinder in its uppermost position. If the machine is left with the pump motor shut off for a substantial length of time, the leakage 15 will permit the cylinder 12 to sink downwardly under the influence of gravity and, accordingly, if that has occurred the flow from line 362 through line 325 and check valve 324 will prefill the upper end of the cylinder and return the 20 cylinder to its top position.

When cylinder 12 reaches its top position and can move no further, the pressure in the upper end of the cylinder in line 137 will build up sufficiently to overcome the force of spring 321 in 25 valve 316, thereby permitting the valve to open and provide communication between ports 318 and 317. Spring 321 is so adjusted, however, that the valve opening cannot occur until the upper end of cylinder 12 is entirely filled and the pressure increases in consequence of the fact that it 30 can raise no further due to mechanical limitations.

When valve 316 opens, the pilot pressure then 35 is transmitted from port 317 through line 364 to a line 365, which extends to channel 225 of valve 40 215. At this point, the fluid is blocked so long as valve 215 is in its neutral position illustrated in the drawings. Communication is also provided between pilot line 364 and port 329 of valve 45 326 by means of a line 366, but so long as the land 328 of valve 326 is in its stop position, illustrated in the drawings, the fluid in line 366 and port 329 is blocked and cannot flow to port 330 or line 368, which connects port 330 to channel 50 223 of valve 215. When valve 215 is in its neutral position, pilot lines 162 and 197 from valves 129 and 141, respectively, are also blocked at channel 221 of valve 215 and, consequently, the valves 129 and 141 will operate only as pressure 55 relief valves. At this time there is no pressure on either pilot line 205 or 209 of valve 143 but the valve spool is retained in its left-hand position by the spring detent 200. Likewise, pilot lines 180 and 183 of valve 132 are connected to the tank.

60 The machine is started by shifting hand lever 243 to the left to its starting position. This shift moves valve spool 230 of valve 215 to the left, opening communication between channels 225 and 224 and allowing the pilot pressure in line 365 to flow through the valve to pilot line 209 at the left-hand end of four-way valve 143. This pilot pressure will immediately shift the valve spool 203 to its right-hand position. However, 65 it should be noted that if the starting handle 243 is shifted to starting position before the cylinder 11 is fully raised, valve 316 will be closed, thus blocking communication between ports 317 and 318 and preventing any flow to the pilot line 365. 70 Accordingly, valve 316 positively prevents a shift 75

of four-way valve 143 until the broaching cylinder 12 is fully elevated by the flow of fluid through line 325, valve 324, line 325', and line 137. As soon as the spool of valve 143 shifts to its right-hand position, the fluid under pressure in line 142 is communicated through valve 143 to line 144 and thence to the right-hand end of the work moving cylinder 26 through the piston rod 28 and opening 146. This will cause the work table to advance the work into broaching position, which position will be determined by engagement of the flat surfaces 76 on the rotatable abutments 74 with the rods 69 which, in turn, engage the fixed abutments 56.

As soon as the work cylinder 26 and the table driven thereby begin to move, the operator may release the starting handle 243, whereupon spring 236 will return the handle and valve spool 230 to their neutral position, shown in the drawings. This will cut off the pilot pressure in pilot line 209 at the left-hand end of valve 143, but the spool 203 will remain in its right-hand position by reason of the engagement of the spring pressed detent 200 in notch 202.

Upon completion of the table advancing movement, push rod 59 will be moved to the right by the rods 60 and will shift the spool 260 of valve 216 to the left, thereby providing communication between channels 251 and 252. Pilot pressure will then flow from line 360 through valve 216 to line 370, which is connected to channel 251 and thence to port 288 of valve 218. From port 288, the pilot pressure flows through passageway 290 to port 289 and thence through line 309, port 310 of valve 301, port 311 of valve 301, and line 180 to the right-hand end of the four-way valve 132. The pilot pressure in pilot line 180 will shift the spool 166 of valve 132 to its left-hand position, thus connecting pressure line 131 with line 134 and connecting tank line 152 with line 133. The fluid under pressure in line 134 flows to the lower end of the broaching cylinder 12 and starts the downward or broaching stroke of the cylinder. During such broaching stroke the fluid in the upper end of the broaching cylinder returns through line 137, valve 136, line 133, valve 132, and the tank line 152. At this time, the return flow of fluid through line 137 will lift the spool 190 of valve 136 off its seat to permit the necessary return flow.

It should be noted that the pilot pressure in line 370 which effected the last mentioned shift of the spool in valve 132 was not only directed to the port 288 of the valve 218, but also, by a branch line 372, to the right-hand end of cylinder 346 through the port 348, thus causing the piston 345 to move to the left to retract the ratchet pawl 343.

It will also be observed that when the work table completed its movement and shifted valve spool 260 of valve 216, it caused a rocking movement of bell crank 266 in a counterclockwise direction, thus returning the lever 119 to its right-hand position by reason of a connecting rod 265, bell crank 264, and rod 121.

Throughout the broaching stroke, fluid under pressure from pump 126 will be maintained in the right-hand end of the work moving cylinder 26 even though the pilot pressure at the left-hand end of valve 143 is eliminated as the result of the shift of spool 260 in valve 216 as well as the return of the starting handle to neutral position. This is due to the fact that the spool 203 of valve 143 will be held in its right-hand position by engagement of the spring pressed detent 200 in

the notch 202, there being no pressure in either of the pilot lines 205 and 209 of valve 203 during the broaching stroke. Accordingly, the work fixture will be held in position by the full operating pressure acting through the self-locking cam slot 23.

On completion of the broaching stroke of cylinder 12, dog 279 engages finger 277 and rotates the spools of valves 217 and 218 in a counterclockwise direction to a position in which the pilot pressure then existing in line 370 (spool 260 of valve 216 being in its left-hand position) flows through port 288 of valve 218 to port 291 of that valve and thence to the pilot line 205, which is connected at the right-hand end of four-way valve 143. The pilot pressure in line 205 will return the spool 203 of valve 143 to its left-hand position, shown in the drawings, thus causing the fluid under pressure from line 142 to pass through valve 143 to the line 145 and through piston rod 29 and opening 147 to the left-hand end of the work moving cylinder 26, thereby causing the work moving cylinder to retract the work table until the cylinder assumes its fully retracted position, shown in the drawings.

Upon completion of the retraction of the work moving cylinder 26, dog 118 engages and shifts lever 119 to the position shown in the drawings, thereby returning spool 260 of valve 216 to its right-hand position illustrated. In that position, the pilot pressure in line 360 is transmitted through valve 216 to line 361 and thence through port 282 of valve 217, port 285 of valve 217, line 308, port 302 of valve 301, passageway 303, and port 305 to pilot line 183, which is connected to the left-hand end of the four-way valve 132.

The pilot pressure in line 183 shifts the spool 166 of valve 132 to its right-hand position, in which fluid under pressure from line 134 passes to line 133 and thence through valve 136 and line 137 to the upper end of the broaching cylinder 12 to cause the broach returning movement. The flow at this time through the valve 136 is from chamber 186 through passageway 187 past the check valve 184 and through passageway 188 and chamber 189. During the broach returning movement, the fluid in the lower end of the cylinder 12 returns through line 134 and the valve 132 to the tank line 152.

At the time the broach returning movement is initiated, the pilot pressure then existing in line 361 is not only transmitted to port 282 of valve 217, but also through branch line 361 to the left-hand end of the indexing cylinder 346, thereby causing the piston 345 to move to the right, carrying its ratchet pawl 343. This right-hand movement of the pawl 343 returns the pawl and piston 345 to the position shown in the drawings and causes the ratchet wheel 342 and disc 337 to rotate clockwise one notch. This rotation of the disc 337 retracts the notch 339 out of engagement with the point 336 on pivoted disc 334, thereby causing the dog to swing in a counterclockwise direction and shift valve spool 327 of valve 326 to the right, thus providing communication between ports 329 and 330.

As will hereafter become apparent, as long as ports 329 and 330 are in communication with each other the machine will automatically repeat its cycle of operations indefinitely.

As soon as broaching cylinder 12 reaches the top of its return stroke, dog 278 engages finger 276, thereby rotating shaft 275 and spools 280 and 281 of valves 217 and 218 in a clockwise direction, returning then to a position shown in the

drawings. Pilot pressure then existing in line 361 may then flow from port 282 of valve 217 through passageway 284 to port 283 and thence through line 362 to line 325. Assuming that the cylinder 12 is in its extreme upward position, the fluid pressure in line 325 will then open valve 316, permitting a flow of fluid from port 318 to port 317 and thence through line 364 to line 366. The pilot pressure in line 366 is transmitted to port 329 of valve 326 and thence to port 330 (and 328 having been shifted to the right) from which it flows through line 368, channel 223 of valve 215, notches 375 in land 233 of the valve spool 230 to channel 224, which communicates with the pilot line 209 for the left-hand end of four-way valve 143. This pilot pressure in line 209 will shift the spool 203 to its right-hand position in order to initiate the work table advancing movement of cylinder 26, thus beginning a new cycle automatically.

The new cycle will follow through in the manner previously described and the piston 345, during such cycle, will operate to advance the pawl 343 and ratchet wheel 342 through one additional notch in a clockwise direction. The cycle will continue to repeat itself with the particular construction shown eleven (11) times, or until the point 336 on pivoted dog 334 drops into notch 339 in the disc 337. This will occur during the eleventh broach returning movement, and will cause the spool 327 of valve 326 to shift to the left, into the position illustrated in the drawings, in which position it blocks communication between ports 329 and 330. When the eleventh broach returning movement is completed, all of the parts of the hydraulic circuit except the ratchet wheel 342 and disc 337 will be returned to the position shown in the drawings, in which position the machine will stop because spool 230 of valve 215 blocks the passage of pilot pressure from line 365 to pilot line 209 for the left-hand end of four-way valve 143.

During the first eleven complete cycles of operation, the work table will have moved on each advancing stroke a slightly greater distance toward the broach than on the preceding advancing stroke, as the result of the action of the surfaces 76 to 86, inclusive, on the rotatable abutments 74. At the end of the eleventh cycle of operation, the surfaces 87 on the rotatable abutments 74 will be in alignment with the rods 60 but out of engagement with the rods because of the fact that the table will be retracted. Since the machine is stopped at this point, the operator may then shift the workpiece from the roughing fixture to the finishing fixture and, having done so, he may again shift the lever 243 to its starting position. The machine will then make a complete cycle of operation and again come to the stop, due to the fact that the ratchet wheel 342 will have returned to the position shown in the drawings, in which the point 336 of pivoted dog 334 rests in notch 339 of disc 337. At this stage, the finished broaching operation will have been completed and all of the parts will have been returned to the position shown in Figure 13. The finished workpiece may then be removed from the machine and a new one inserted, and the machine is ready to begin a complete new cycle of operation.

It will be understood that the ratchet wheel 342 will be provided with the same number of teeth as there are provided abutment surfaces on the rotatable abutment 74 and that the disc 337 will be provided with notches around its periphery at all points at which it is desired to

bring the machine to a stop. Thus, for example, when the modified form of abutment cam illustrated in Figure 12 is employed, the valve 326 will be provided with a ratchet wheel 342' having eight teeth, as shown in Figure 14, and the disc 337' will be provided with four equally spaced notches 339'. The notches 339' are positioned to be engaged by the pawl 334 during the return of the broaching ram on every other broach return stroke. Thus, the machine will stop at the completion of each pair of broach cutting operations in order to give the operator an opportunity to replace the finished work with a new workpiece.

It will be apparent that there is provided in accordance with the present invention an improved and highly efficient machine for making a plurality of successive broaching cuts in a single workpiece. The machine may be readily adapted to operate through any desired number of broaching strokes by simply changing the rotatable abutments, the ratchets for driving the rotatable abutments, and the ratchet 342 and disc 337 in the indexing mechanism of the hydraulic circuit.

It will be apparent that various alterations and modifications in the construction of the machine may be indulged in without departing from the spirit of the invention or the scope of the appended claims.

What is claimed is:

1. In a broaching machine for making a plurality of successive cuts on a workpiece with the same broaching tool, a frame, a broaching tool movable in a fixed path, a work holding fixture movable with respect to said frame toward and away from the path of movement of said broach, means to force said fixture toward said path, co-operating abutments on said fixture and frame, respectively, adapted to limit movement of said fixture toward said path, one of said abutments including a rotary member having a peripheral abutment surface which at successive points circumferentially of said member is located at progressively decreasing distances from the axis of rotation of said member, and means operable when said fixture is withdrawn from said path to rotate said member by a predetermined amount in order to increase the next succeeding movement of the fixture toward said path.

2. In a broaching machine for making a plurality of successive cuts on a workpiece with the same broaching tool, a frame, a broaching tool movable in a fixed path, a work holding fixture movable with respect to said frame toward and away from the path of movement of said broach, means to force said fixture toward said path, co-operating abutments on said fixture and frame, respectively, adapted to limit movement of said fixture toward said path, one of said abutments including a member journaled for rotation about an axis and having a periphery provided with a series of plane abutment surfaces located at progressively decreasing distances from said axis, and means operable when said fixture is withdrawn from said path to rotate said member from a position in which one of said plane abutment surfaces is in position to co-operate with the other abutment to limit movement of the fixture toward said path to a position in which the next succeeding plane surface of lesser distance from said axis is in position to co-operate with the other abutment.

3. In a broaching machine for making a plurality of successive cuts on a workpiece with the same broaching tool, a frame, a broaching tool

movable in a fixed path, a work holding fixture movable with respect to said frame toward and away from the path of movement of said broach, means to force said fixture toward said path, co-operating abutments on said fixture and frame, respectively, adapted to limit movement of said fixture toward said path, one of said abutments including a member journaled for rotation about an axis and having a periphery provided with a series of plane abutment surfaces located at progressively decreasing distances from said axis and intersecting, respectively, at right angles a corresponding series of equally spaced co-planar radii extending from said axis, and means operable when said fixture is withdrawn from said path to rotate said member from a position in which one of said plane abutment surfaces is in position to co-operate with the other abutment to limit movement of the fixture toward said path to a position in which the next succeeding plane surface of lesser distance from said axis is in position to co-operate with the other abutment.

4. In a broaching machine for making a plurality of successive cuts on a workpiece with the same broaching tool, a frame, a broaching tool movable in a fixed path, a work holding fixture movable with respect to said frame toward and away from the path of movement of said broach, means including a self-locking cam for moving said fixture toward said path, said cam being adapted to move said fixture to and lock it in a plurality of broaching positions varying in distance from said path, co-operating abutments on said fixture and frame, respectively, adapted to limit movement of said fixture toward said path, one of said abutments including a rotary member having a peripheral abutment surface which at successive points circumferentially of said member is located at progressively decreasing distances from the axis of rotation of said member, and means operable when said fixture is withdrawn from said path to rotate said member by a predetermined amount in order to increase the next succeeding movement of the fixture toward said path.

5. In a broaching machine for making a plurality of successive cuts on a workpiece with the same broaching tool, a frame, a broaching tool movable in a fixed path, a work holding fixture movable with respect to said frame toward and away from the path of movement of said broach, means including a self-locking cam for moving said fixture toward said path, said cam being adapted to move said fixture to and lock it in a plurality of broaching positions varying in distance from said path, co-operating abutments on said fixture and frame, respectively, adapted to limit movement of said fixture toward said path, one of said abutments including a member journaled for rotation about an axis and having a periphery provided with a series of plane abutment surfaces located at progressively decreasing distances from said axis, and means operable when said fixture is withdrawn from said path to rotate said member from a position in which one of said plane abutment surfaces is in position to co-operate with the other abutment to limit movement of the fixture toward said path to a position in which the next succeeding plane surface of lesser distance from said axis is in position to cooperate with the other abutment.

6. In a broaching machine for making a plurality of successive cuts on a workpiece with the same broaching tool, a frame, a broaching tool movable in a fixed path, a work holding fixture

movable with respect to said frame toward and away from the path of movement of said broach, means including a self-locking cam for moving said fixture toward said path, said cam being adapted to move said fixture to and lock it in a plurality of broaching positions varying in distance from said path, co-operating abutments on said fixture and frame, respectively, adapted to limit movement of said fixture toward said path, one of said abutments including a member journaled for rotation about an axis and having a periphery provided with a series of plane abutment surfaces located at progressively decreasing distances from said axis and intersecting, respectively, at right angles a corresponding series of equally spaced co-planar radii extending from said axis, and means operable when said fixture is withdrawn from said path to rotate said member from a position in which one of said plane abutment surfaces is in position to co-operate with the other abutment to limit movement of the fixture toward said path to a position in which the next succeeding plane surface of lesser distance from said axis is in position to co-operate with the other abutment.

7. In a broaching machine for making a plurality of successive cuts on a workpiece with the same broaching tool, a frame, a broaching tool movable in a fixed path, a work holding fixture movable with respect to said frame toward and away from the path of movement of said broach, means to force said fixture toward said path, a fixed abutment on said frame, and abutment means on said fixture including a rotary member having a peripheral abutment surface which at successive points circumferentially of said member is located at progressively decreasing distances from the axis of rotation of said member, and means operable when said fixture is withdrawn from said path to rotate said member by a predetermined amount in order to increase the next succeeding movement of the fixture toward said path.

8. In a broaching machine for making a plurality of successive cuts on a workpiece with the same broaching tool, a frame, a broaching tool movable in a fixed path, a work holding fixture movable with respect to said frame toward and away from the path of movement of said broach, means to force said fixture toward said path, a fixed abutment on said frame, and abutment means on said fixture including a rotary member having a peripheral abutment surface which at successive points circumferentially of said member is located at progressively decreasing distances from the axis of rotation of said member, means operable when said fixture is withdrawn from said path to rotate said member by a predetermined amount in order to increase the next succeeding movement of the fixture toward said path, means for moving said broaching tool in said path through a broaching stroke, and control means for initiating the broaching stroke operation of said last named means, and said control means including an element operated by the abutment means on said fixture to initiate the broaching stroke when said abutment means engages said fixed abutment.

9. In a broaching machine for making a plurality of successive cuts on a workpiece with the same broaching tool, a frame, a broaching tool movable in a fixed path, a work holding fixture movable with respect to said frame toward and away from the path of movement of said broach, means to force said fixture toward said path, a

fixed abutment on said frame, and abutment means on said fixture including a rotary member having a peripheral abutment surface which at successive points circumferentially of said member is located at progressively decreasing distances from the axis of rotation of said member, means operable when said fixture is withdrawn from said path to rotate said member by a predetermined amount in order to increase the next succeeding movement of the fixture toward said path, means for moving said broaching tool in said path through a broaching stroke, and control means for initiating the broaching stroke operation of said last named means, said fixed abutment having an opening through the abutment face thereof, and said control means including an element projecting through said opening in the fixed abutment and operated by the abutment means on said fixture to initiate the broaching stroke when said abutment means engages said fixed abutment.

10. A broaching machine for making a plurality of successive cuts with the same broaching tool, including a movable broaching tool holder, a work fixture movable toward and away from the broach, means for forcing the work table toward the broach, an abutment mounted on a stationary portion of the machine, a rotatable member journaled on said fixture and having a periphery adapted to co-operate with said first mentioned abutment when said fixture is moved toward said position to limit such movement, the periphery of said member at successive points circumferentially thereof being located at progressively decreasing distances from the axis of rotation of said member, and means operable when said fixture is withdrawn from said position for rotating said member by a predetermined amount in order to increase the next succeeding movement of the fixture toward the broach.

11. In a broaching machine for making a plurality of successive cuts on a workpiece with the same broaching tool, a frame, a broaching tool mounted on said frame for movement in a fixed path, a work moving table reciprocable on said frame toward and away from said path at right angles to said path, means connected to said table in approximate alignment with the center of the broaching tool for forcing the table toward the broach, a shaft journaled on the table and extending transversely to the direction of movement of the table on opposite sides of the connection between the table and said means, a pair of fixed abutments on the frame of the machine on opposite sides of the broach, and a pair of co-operating abutment members on said shaft, each of said co-operating abutment members having a peripheral abutment surface which at successive points circumferentially of said member is located at progressively decreasing distances from the axis of said shaft, and means to rotate said shaft a predetermined amount on each reciprocation of the table to cause said table to advance further toward said broach on each of a plurality of successive reciprocations before said co-operating abutments engage said fixed abutments.

12. In a broaching machine for making a plurality of successive cuts on a workpiece with the same broaching tool, a frame, a broaching tool mounted on said frame for movement in a fixed path, a work moving table reciprocable on said frame toward and away from said path at right angles to said path, means connected to said table in approximate alignment with the center

of the broaching tool for forcing the table toward the broach, said means including a fluid pressure driving motor and a self-locking cam adapted to lock the table against movement in response to the broach cutting pressure, a shaft journaled on the table and extending transversely to the direction of movement of the table on opposite sides of the connection between the table and said means, a pair of fixed abutments on the frame of the machine on opposite sides of the broach, and a pair of co-operating abutment members on said shaft, each of said co-operating abutment members having a peripheral abutment surface which at successive points circumferentially of said member is located at progressively decreasing distances from the axis of said shaft, and means to rotate said shaft a predetermined amount on each reciprocation of the table to cause said table to advance further toward said broach on each of a plurality of successive reciprocations before said co-operating abutments engage said fixed abutments.

13. In a broaching machine for making a plurality of successive cuts on a workpiece with the same broaching tool, a frame, a broaching tool mounted on said frame for movement in a fixed path, a work moving table reciprocable on said frame toward and away from said path at right angles to said path, means connected to said table in approximate alignment with the center of the broaching tool for forcing the table toward the broach, a pair of abutments mounted on the frame at opposite sides of the path of movement of the broach and a second pair of abutments mounted on the table in position to co-operate with the first pair, one of said pairs of abutments being fixed and the other comprising a pair of elements mounted on a common rotatable shaft, each of said elements having a peripheral abutment surface which at successive points circumferentially of said member is located at progressively decreasing distances from the axis of said shaft, and means to rotate said shaft a predetermined amount on each reciprocation of the table to cause said table to advance further toward said broach on each of a plurality of successive reciprocations before said co-operating abutments engage said fixed abutments.

14. In a broaching machine for making a plurality of successive cuts on a workpiece with the same broaching tool, a frame, a broaching tool mounted on said frame for movement in a fixed path, a work moving table reciprocable on said frame toward and away from said path at right angles to said path, means connected to said table in approximate alignment with the center of the broaching tool for forcing the table toward the broach, said means including a fluid pressure driving motor and a self-locking cam adapted to lock the table against movement in response to the broach cutting pressure, a pair of abutments mounted on the frame at opposite sides of the path of movement of the broach and a second pair of abutments mounted on the table in position to co-operate with the first pair, one of said pairs of abutments being fixed and the other comprising a pair of elements mounted on a common rotatable shaft, each of said elements having a peripheral abutment surface which at successive points circumferentially of said member is located at progressively decreasing distances from the axis of said shaft, and means to rotate said shaft a predetermined amount on each reciprocation of the table to

cause said table to advance further toward said broach on each of a plurality of successive reciprocations before said co-operating abutments engage said fixed abutments.

15. In a broaching machine for automatically performing a broaching cycle including a plurality of broaching strokes on the same workpiece, a stationary frame, a reciprocating work fixture adapted to move the workpiece toward and from the path of travel of the broach, means to move the work fixture into broaching position in advance of each broaching stroke and to retract it from broaching position in advance of each broach return stroke, and means including a pair of abutments located on the work fixture and the frame, respectively, for limiting movement of the fixture toward broaching position, one of said abutments including a rotatable member having a plurality of peripheral abutment areas each adapted to engage the other abutment member in one rotative position of said rotatable member, said abutment areas being in number equal to an even multiple of the number of strokes of the work fixture in a complete broaching cycle and not less than six, a ratchet wheel connected to said rotatable member and having the same number of teeth as there are abutment areas on the member, and a pawl mounted on said frame for indexing said ratchet wheel on each reciprocation of said fixture, said abutment areas being located at varying distances from the axis of said rotatable member to permit the fixture to move progressively closer to the broach on each reciprocation during a complete broaching cycle and on the indexing movement following the last broaching stroke of each cycle to limit movement of the fixture toward the broach at the point required to make the first broaching cut of the next broaching cycle.

16. In a broaching machine for automatically performing a broaching cycle including a plu-

rality of broaching strokes on the same workpiece, a stationary frame, a reciprocating work fixture adapted to move the workpiece toward and from the path of travel of the broach, means 5 for reciprocating the work fixture including a cam and a hydraulic piston and cylinder unit for operating the cam, said cam having a self-locking portion adapted to hold the work fixture against return movement under the influence of 10 the pressure exerted by the broaching teeth, said means being adapted to move the work fixture into broaching position in advance of each broaching stroke and to retract it from broaching position in advance of each broach return stroke, 15 and means including a pair of abutments located on the work fixture and the frame, respectively, for limiting movement of the fixture toward broaching position, one of said abutments including a rotatable member having a plurality 20 of peripheral abutment areas each adapted to engage the other abutment member in one rotative position of said rotatable member, said abutment areas being in number equal to an even multiple of the number of strokes of the work fixture in a complete broaching cycle and not less than six, a ratchet wheel connected to 25 said rotatable member and having the same number of teeth as there are abutment areas on the member, and a pawl mounted on said frame for indexing said ratchet wheel on each reciprocation of said fixture, said abutment areas being located at varying distances from the axis of said 30 rotatable member to permit the fixture to move progressively closer to the broach on each reciprocation during a complete broaching cycle and on the indexing movement following the last broaching stroke of each cycle to limit movement 35 of the fixture toward the broach at the point required to make the first broaching cut of the next broaching cycle.

HARRY H. GOTBERG.

CERTIFICATE OF CORRECTION.

Patent No. 2,358,225.

September 12, 1944.

HARRY H. GOTBERG.

It is hereby certified that error appears in the printed specification of the above numbered patent requiring correction as follows: Page 2, first column, line 39, for "casing" read --casting--; page 3, first column, line 31, for "uringing" read --urging--; page 7, first column, line 64-65, for "passagefay" read --passageway--; page 8, first column, line 36, for "stopped in" read --stopped to--; and second column, line 73, for "blacking" read --blocking--; and that the said Letters Patent should be read with this correction therein that the same may conform to the record of the case in the Patent Office.

Signed and sealed this 7th day of November, A. D. 1944.

Leslie Frazer

(Seal)

Acting Commissioner of Patents.
